UNITED STATES PATENT OFFICE.

FRANK W. LEV, OF ASTORIA, NEW YORK, ASSIGNOR TO INTERNATIONAL PACKING MACHINE COMPANY, OF NEW YORK, N. Y., A CORPORATION OF NEW YORK.

WRAPPING MACHINE.

Application filed June 2, 1920. Serial No. 386,023.

To all whom it may concern:

Be it known that I, FRANK W. LEV, a citizen of the United States, residing at Astoria, Long Island, in the county of 5 Queens and State of New York, have invented certain new and useful Improvements in Wrapping Machines, of which the following is a specification.

This invention relates to machinery for 10 wrapping packages of cigarettes and the like.

The principal objects of the invention are to provide a machine of this character, which will operate rapidly and efficiently to 15 automatically apply wrappers, labels or the like, and which will be of durable and relatively simple construction.

In the form of the invention which I have herein disclosed, the wrappers are fed from 20 a wrapper magazine into position in front of a pusher which doubles the wrapper over the articles and forces the same into folding boxes provided in a traveling carrier. These boxes are constructed with corner 25 folders which turn in the corners at the forward edge of the wrapper. The carrier is then advanced to carry the inserted wrappers into position in line with a second set of corner folders. In the course of travel of 30 the wrappers from the first station to this second station, the ends of the wrapper are brought together and at the second station, another pusher ejects the wrappers past this second set of corner folders, so 35 as to turn in the rear corners of the package. In this ejecting movement, the wrappers are carried past edge-folding devices which close the edges of the wrapper together, after which the closed wrappers are 40 ejected by a packer onto a suitable carrying off conveyor.

In the accompanying drawings I have 45 illustrated the invention embodied in this one form, but I would have it understood that various changes and modifications may be made without departure from the true spirit and scope of the invention as herein defined and claimed.

In the drawings referred to:

50 Figure 1 is a top plan view of the machine, with parts indicated as broken away and shown in section.

Figure 2 is a view looking toward that side of the machine which appears at the

bottom in Figure 1, parts here also being 55 indicated as broken away and appearing in section.

Figure 3 is a view of the opposite side of the machine, with parts broken away and in 60 section.

Figure 4 is a partly broken view looking at the right hand end of the machine shown in Figure 1.

Figure 5 is a broken side elevation of the 65 wrapper magazine.

Figure 6 is a sectional view of the same, on substantially the plane of line 6—6 of Figure 5.

Figures 7, 8, 9 and 10 are broken detail views illustrating successive operations in 70 the formation of the package.

Figure 11 is a perspective view of the package ready to have the final fold made.

Figure 12 is a detail view illustrating the 75 operation of the final folders.

Figure 13 is a perspective view of the completed package.

Figure 14 is a broken detail view of the adjustable gage for the wrappers.

The machine herein disclosed is designed 80 for the packaging of cigarettes and involves a combination of related devices, by which the cigarettes are bundled and each bundle is wrapped in a single cover.

The articles to be packed or labeled, in 85 this case the cigarettes, are supported in a hopper or magazine 15, which may be of the type consisting of a box-like structure which is agitated by means of a crank 16 and rocking lever 17, to cause the cigarettes 90 to feed down evenly in the compartments between the partitions 18, from which they are ejected by the multi-fingered plungers 19, to a chamber where the two rows of cigarettes thus ejected are combined by the 95 co-operating slides 20 into a bundle, such as indicated at 21 in Figure 14.

The bundle thus formed, and while held in this shape within the guide channel provided therefor, is engaged by the plunger 22 100 and advanced against a previously positioned wrapper or label 23, serving as it is thus advanced to double the wrapper over the forward end of the same and to carry the doubled wrapper into a folding box or 105 pocket.

These folding boxes are designated 24 and consist of open ended compartments connect-

ed to form an endless chain supported on the sprocket wheels 25 and 26.

The boxes are shown as rigidly constructed elements mounted on a flexible supporting band or belt 27 and are each shown as secured to said band along a single line 28 (Figures 3 and 7), substantially transverse to the line of flexure of the band in passing over the sprockets or pulleys, so as not to interfere with the flexing of the belt. Interfitting lugs and sockets on the belt and supporting sprockets maintain the parts in proper relation and also serve as driving means. In the illustration the seats or recesses are shown at 29, as formed in the sprockets and the lugs are indicated at 30 in the form of cleats secured to the under face of the flexible band in line with the fastening of the folding boxes thereto. For the sake of simplicity, the same fastenings which secure the boxes in place may be extended through to fasten the lugs at the under side of the belt, substantially as I have indicated at 31 in Figure 7.

25 The carrier described is intermittently advanced with a step by step motion to carry the folding boxes to and past the different folding instrumentalities by means consisting in the illustration of Geneva gearing, involving a disc 32 carrying a pin 33 engaging at each revolution of the disc in a slot 34 in the carrier sprocket 26 and having an arcuate rim or flange 35 taking into the arcuate pockets 36 in the side of the sprocket at the end of each shifting movement, to hold the sprocket stationary for the balance of the revolution of the disc.

40 The wrappers or labels 23 are automatically fed one by one from the magazine 37 by feeding-out devices consisting in the illustration of a plurality of frictional belts 38 of rubber or the like (Figures 4, 5 and 6) supported on pulleys 38^a with their upper runs standing above or substantially in the plane of the bottom of the magazine, so as to engage the lowermost wrapper therein. The pulleys for these friction belts are carried by the shafts 39 and an intermittent feeding operation is obtained by intermittently rotating these shafts in a feeding-out direction.

45 This intermittent feeding movement is imparted to the shafts 39 from a reciprocating rack 40 mounted in guides 41 on the side of the magazine and engaging with the gears 42 carried by the sleeves 43 loose on the shafts and which sleeves carry the discs 44, supporting spring-pressed pawls 45 in engagement with the ratchets 46 fast on the ends of the shafts. These pawls and ratchets are faced so as to operate the conveyor shafts only in the feeding-out direction or toward the right in Figure 5.

50 The wrappers separated by the feeding-out devices are advanced to the station where

they are acted on by the feed plunger 22 (Figure 14) through a guide-way, including the opposed sets of conveyor belts 47-48 which may be constantly driven and which extend down far enough to drop the wrappers accurately in the stationary guide channels 49.

55 In the illustration I have utilized this constant drive of the feed belts to effect the reciprocating movement of the feeding-out rack. The connections for this purpose, as best shown in Figure 5, comprise a crank disc 50 driven by gears 51 from the upper belt pulley and connected by a pivoted link 52 with the end of the rack. With this construction, the rack is being continually reciprocated back and forth, but serves through the ratchet connections to operate the wrapper-separating and feeding-out devices only on the outward strokes of the 85 rack.

60 The constantly operating wrapper advancing belts are shown as driven from an upright shaft 53 through bevel gearing 54 and a shaft 55 connected by gearing 56 with the belt carrying rolls or pulleys, the two opposed sets of belts being connected by a suitable chain of gearing, such as I have indicated at 57.

65 The wrappers are properly registered in front of the pockets in the conveyor by a suitable gage or gages, such as shown in Figure 14, in the form of stop pins 58 carried by the plates 59 adjustably secured by the thumb screws 60 at the lower ends of the 100 guide channels 49. The adjustability of these registering devices enables the adaptation of the machine to different sizes or styles of labels and the independent adjustment of the two stops is important in that it enables the wrapper to be "tilted" one way or the other until the proper effect is obtained.

70 The first wrapper applying operation consists in forcing the article or packet against the previously positioned wrapper and into one of the folding boxes in the carrier, so as to double the wrapper over the forward or leading edge of the article. This condition is illustrated in Figure 7, wherein the article feeding plunger 22 is shown as having forced the bundle of cigarettes far enough into the folding pocket to double the wrapper over the top and bottom of the 115 bundle.

75 As the doubled wrappers are inserted in the folding boxes, the forward corners thereof are broken and turned in by corner folders 61 mounted in opposed relation in the folding boxes at the side furthest from the feeding-in plunger 22. These corner folders are shown in the form of blocks or lugs extending inward into the box from the opposite side walls thereof and having opposed substantially flat and parallel side 120

faces 62 to shape and confine the sides of the entering package and tapered or wedge shape forward ends 63 operating as wedges to form the preliminary break in the advance edge of the wrapper. Spaces 64 are left in the folding boxes above and below the corner fold blocks for the laterally extending side wings 65 of the entering wrapper.

10 The folding boxes may be conveniently constructed as best shown in Figure 7 in the form of substantially U-shaped castings or members having the inwardly extending folding blocks 61 carried by the opposite sides thereof and having the tops closed by plates 66 which may be secured in place by screws or other suitable fastenings 67. This makes the construction of these boxes relatively inexpensive 15 and at the same time enables the boxes to be readily opened up to gain complete access to the corner folders, in case, for instance, it is found that said folders are not operating properly.

20 After the wrappers with the contained articles are fully seated in the folding boxes, and the forward corners of the wrapper have been thereby broken in and shaped, the carrier is advanced by the intermittent 25 movement described, to carry the projecting upper rear edge 68 of the wrapper beneath a down turned folding flange 69 (Figure 7) which turns the edge down over the rear end of the article into the form of an end flap, as shown in Figure 8.

In the next advancing movement of the carrier, the lower rearwardly extending flap 70 of the wrapper is carried beneath a pasting device shown in the form of an adhesive applying roller 71 which applies 40 a strip of adhesive 72 to such lower flap.

45 As the wrapper under consideration is further advanced, a flap turner 73 folds the lower flap 70 up over the down turned flap 68, as shown in Figure 9, thereby completing the closing of the rear end of the wrapper. With the rear end thus closed, the package wrapper is then brought into registry with a slide which ejects it from the 50 folding pocket.

The construction and operation of this ejecting slide will be best understood from Figures 1 and 10, wherein, the slide is indicated at 74 and is shown standing at the opposite side of the conveyor from the feeding-in slide and in position to engage and eject the package from the folding box, which is then in registry therewith.

55 As the packages are ejected by this slide, they pass into a channel indicated generally at 75 in Figure 1, and in which are arranged first, a set of rear edge corner folders 76, then a set of down turning flap folders 77 and finally, a set of up turning flap folders 78 (Figures 10 and 12).

As the package passes beneath the upper flap folders 77 (Figure 10), the lower outstanding flaps 65 pass under the glue or adhesive applying rolls 79 and receive a strip of adhesive, as indicated, so that said flaps 70 are in condition to seal the package when acted on by the final folders 78 upon the next movement of the package.

The packages after being thus completely sealed, pass out the end of the guide passage 75 beneath a plunger 80 (Figures 1 and 2) which delivers the completed packages through a chute 81 onto the carrying-off conveyor 82.

From the foregoing it will be seen that 80 the carrier with the folding boxes is intermittently advanced to bring the same into register with the several folding devices. At the first station, a wrapper is automatically fed out of the magazine and positioned 85 in front of the open end of a folding box. The feeding plunger then advances and forces the previously formed bundle of cigarettes into the folding box and against the wrapper, so as to fold the same across 90 the leading end and over the top and bottom of the bundle. In this feeding-in movement, the forward corners of the wrappers are turned in and folded by the corner 95 folders in the opposite sides of the box (Fig. 7). As the carrier advances in its next movement, the upper rearward edge 68 of the wrapper is turned downward by the stationary flap folder 69.

In the next advancing movement of the carrier, the lower rearward edge 70 of the wrapper is carried beneath the pasting roller 71 (Fig. 8) and on the succeeding advancing movement of the carrier this lower pasted flap is turned up by the flap turner 73, 105 so as to close the rearward end of the package. The package is now in condition to be discharged from the conveyor chain, which operation takes place when the chain has advanced to bring the package into register 110 with the ejecting slide 74. This slide, in ejecting the wrapper with its contents, forces the rearward closed end of the wrapper past the corner folders 76 which turn in the rear corners of the package, as shown 115

in Figure 10. The stroke of the pusher 74 may be just sufficient to discharge the package from the folding pocket, the advancing movement of the packages through the discharge channel 75 being accomplished by 120 the engagement of one package against another. After passing the rear set of corner folders 76, the upper flaps 65 of the wrapper are turned down by the flap folders 77 over the turned in corners, the lower outstanding flaps receive a supply of adhesive and then in the further movement of the packages, the final folders 78 turn up the lower adhesive flaps 65 and thus seal the package. The discharge channel 75 may be arranged to fit 130

the packages rather closely, so as to insure their being properly sealed and it is for this reason that the packing plunger 80 is provided, to positively eject the finished packages from such channel.

It is, of course, important that the folding pockets shall be exactly registered with the various folding devices and particularly with the feeding-in and ejecting plungers. 10 This is effected by the Geneva gearing disclosed, which advances the carrier a definite amount at each operation and then locks the carrier momentarily in the advanced position, and while the folding devices are operating on the wrappers in the pockets.

The various related instrumentalities described are all mounted on a suitable base or framework and suitably connected so as to operate in properly timed relation. In 20 the machine herein disclosed, I have illustrated a suitable supporting framework at 83 and have shown the parts as all driven from a main power shaft 84 on which are mounted the fast and loose pulleys 85—86 respectively. This main power shaft drives through spur gearing 87, a cross shaft 88 connected by bevel gearing 89 with a longitudinally extending shaft 90 and which latter shaft drives through bevel gearing 91, the cross shaft 92 which carries the disc 32 of the Geneva gearing for operating the carrier. This cross shaft 92 is shown as utilized also for driving the carrying-off conveyor 82 through sprocket chain connections indicated at 93.

The feeding-in slide 19 is operated through a link connection 94, from the rocking arm 95, which is mounted on rock shaft 96, said latter shaft being actuated through a rock arm 97 and connecting link 98 from a crank disc 99 on the end of shaft 90.

The ejecting pusher 74 is shown as operated through a connecting link 100 from rocker arm 101 on rock shaft 102 which is connected by gearing 103 with the first rock shaft 96.

The upright shaft 53 which drives the magazine feed rollers is shown as driven by bevel gearing 104 (Fig. 3) from the cross shaft 88.

The first set of gluing rollers is driven, in the illustration, through a system of gearing 105 (Fig. 3) from a transverse shaft 106 connected by suitable bevel gearing with the upright shaft 53.

The second set of adhesive applying rollers are shown in Figure 1 as driven by gearing 107 from a longitudinally extending shaft 108 driven by bevel gearing 109 from the upright shaft 53.

The crank disc 16 for agitating the hopper is illustrated as carried by a shaft 110 connected by bevel gearing 111 with the longitudinal shaft 108.

65 The packing slides 20 which bundle the

cigarettes into the form shown in Figure 14, are actuated in the illustration by a rocking lever 112 shown in Figure 2 as operated by a cam 113 on the cross shaft 88, said cam lever being directly connected at its upper end with the left hand slide 20 in Figure 1 and serving through the rack and pinion gearing illustrated at 114 to operate the reversely acting right hand slide 20.

The discharging plunger 80 is illustrated 75 in Figure 2 as operated by a rock arm 115 on rock shaft 96 connected by a link 116 with the lower end of the sliding rod 117 which supports the plunger.

In my invention the operations are entirely automatic and in view of the results accomplished, it will be seen that the machine is of relatively simple construction. The parts are all durable and not likely to get out of order and may be driven at relatively high speed without impairing the work turned out by the machine.

What I claim is:

1. In a wrapping machine, the combination of an endless traveling carrier having 90 open ended folding boxes provided with corner folders, means for forcing articles in one direction into the folding boxes and against wrappers which are being folded thereabout, the said wrappers being forced past said corner folders to thereby turn in the front corners of the wrappers, rear corner folders located at the side of the carrier and in position to register with the rearward corners of the wrapper projecting 95 beyond the articles, and means operated simultaneously with and by the movement of said first means for ejecting the partially wrapped package from the folding boxes past said second set of corner folders to 100 fold the opposite corners of the wrappers 105 against the articles.

2. In a wrapping machine, a traveling endless carrier having folding boxes provided with corner folders, means located at 110 one point in the travel of the carrier for feeding articles against wrappers and into said boxes to fold the wrappers about the articles, the wrappers being forced past the corner folders during their movement into 115 the boxes, a second set of corner folders adjacent the path of travel of the carrier and located at a point removed from said first means, means for shifting the carrier in a step by step movement to register one box 120 with said second set of corner folders simultaneously with another box being brought into register with the first named means, and means operating simultaneously with the operation of the first means for ejecting 125 the partially wrapped articles from the folding boxes and past the second set of corner folders.

3. In a package forming machine, an 130 endless conveyor having a series of folding

boxes provided with corner folders adjacent the ends thereof, means for forcing articles against wrappers to fold the latter about one end and over the opposite faces 5 of the articles and for inserting the same with the doubled end foremost into the opposite end of the box and past the corner folders, means for bringing the ends of the wrapper together over the opposite end of 10 the articles and to close the wrapper into a package, rear-corner folders at the receiving end of the box opposite the front corner folders and arranged to register therewith, there being at the same time a box in register with 15 the first means, and means cooperating with the movement of said first means to simultaneously eject the partially wrapped package from the box while another wrapper is being forced into a box by the operation of 20 the first means and to carry the closed rear end of the said partially wrapped package past the rear end corner folders.

4. In a packaging machine, a series of folding boxes having corner folders, means 25 for forcing articles against wrappers to fold the latter about the rear edges of the articles and over the opposite faces thereof and for simultaneously forcing the article and wrapper into one of said boxes and past the 30 corner folders, means for bringing the ends of the wrapper together about the ends of the contents to close the end of the package opposite that engaged by the corner folders, a second set of corner folders, means for 35 relatively shifting the folding boxes to bring the last closed end of the package into registry with said second set of corner folders, ejecting means for forcing the package out of the folding boxes past the second set of 40 corner folders, and means for imparting simultaneous movement to the first named means and ejecting means, whereby for each 45 cycle of operation articles are being forced into one folding box while other partially wrapped articles are being ejected from a box past the second set of corner folders.

5. In a machine of the character described, a series of corner folders arranged in pairs, said folders being capable of lateral movement through said machine, means 50 for forcing a package against a wrapper and into engagement with the corner folders to break in the corners at the forward end of the wrapper, a pair 55 of corner folders aligned with the members of the movable series of folders as the latter move into register therewith, means for advancing the series of folders toward the last named pair of corner folders, means 60 for forcing the partially wrapped package in the reverse direction past said pair of corner folders to break in the rearward corners of the wrapper and means for imparting simultaneous movement to the mechanisms 65 for forcing a package against a wrap-

per while another package is being moved in a reverse direction past the said pair of folders.

6. In a machine of the character described, a series of corner folders arranged 70 in pairs, means for forcing a package against a wrapper to fold the latter about the package and then past corner folders to break in the corners at the forward edge thereof, a second pair of corner folders 75 apart from the pairs of the other series, means for forcing the partially wrapped package in the reverse direction past said second set of corner folders to break in the rearward corners of the wrapper, said second set of corner folders being offset with respect to the members of the said series of folders, means for transporting in a step by step movement the partially wrapped package from the first means to second means, and 80 means for simultaneously operating the first and second means whereby a package may be forced into engagement with one pair of corner folders of the series while another package is being ejected from another pair 85 of folders of the series.

7. In a wrapping machine, pairs of corner folders for the forward corners of package wrappers, a pair of corner folders for the rearward corners of the package wrappers, means for producing relative shifting movement of the wrappers and pairs of corner folders with respect to the other pair of folders for the rearward corners of the wrappers, means for producing simultaneous shifting movement of the wrappers with 90 respect to the pairs of corner folders and the second mentioned pair of corner folders to break in the front and rear corners of the wrappers, and means enclosing the said rear corner folders for folding in first one of the sides of the wrapper over said turned-in corners and then folding in the other of the sides to lie over said first named sides. 95

8. In a wrapping machine, pairs of corner folders, means for simultaneously folding a wrapper about an article to form a package and forcing the folded edge of the wrapper past said corner folders to break in the forward corners of the wrapper, means for securing the ends of the wrapper together, a second pair of corner folders, means including a pair of complementary gears operated simultaneously with the movement of said first means for forcing the wrapper backward past said second pair of corner folders to turn in the rearward corners of the package, and means enclosing said rear corner folders for turning in the sides of the wrapper over said folded-in corners. 105

9. In a wrapping machine, folding boxes provided with corner folders, a pusher for forcing articles against a wrapper to fold the latter about the articles to form a package and to insert the package into a folding 110

box and past the corner folders, means for securing together the free ends of the wrapper, a second set of corner folders at one side of said pusher, means for shifting the folding boxes from the plane of said pusher into the plane of said second set of corner folders, a second pusher entering between the first corner folders to force the wrapper out of the folding box and past the second set of corner folders, and means for simultaneously operating both pushers.

10. In a wrapping machine, an endless carrier having a plurality of folding boxes provided with corner folders, means for intermittently advancing said carrier, a pusher at one of the rest stations of said carrier arranged to force articles against a wrapper and simultaneously insert the package into the folding boxes past the said corner folders, a second set of corner folders positioned at a second rest station of the carrier at one side of said pusher, means operating in the travel of the carrier between said stations to close the ends of the folded wrapper, and means controlled by the movement of said pusher and located at said second station for ejecting the package from the folding box and past the second set of corner folders, whereby the movement of said last named means may be simultaneously effected with the operation of said pusher.

11. In a wrapping machine, an endless carrier having a plurality of folding boxes provided with corner folders, means for intermittently advancing said carrier, a pusher at one of the rest stations of said carrier arranged to force a package against a wrapper and insert the same into the folding boxes past said corner folders, a second set of corner folders positioned at a second rest station of the carrier at one side of said pusher, means operating in the travel of the carrier between said stations to close the ends of the folded wrapper, means at the said second station for ejecting the wrapper from the folding box and past the second set of corner folders, means operatively connected to the pusher and the last means for simultaneously operating both elements to insert and eject a wrapper at the same time, and means in line with the travel of the packages past said second set of corner folders for securing the edges of the wrapper together over the turned-in corners.

12. In a wrapping machine, an endless carrier provided with folding boxes, a pusher at one side of said carrier for forcing articles against a wrapper and inserting the articles and wrapper into the folding boxes, a pusher simultaneously movable with said first pusher and at the opposite side of the carrier for ejecting the wrappers from said boxes, and means operating in conjunction with said pushers for turning in the corners 65 of the wrappers as they are inserted into and

ejected from said folding boxes and comprising oppositely disposed front corner folders in the folding boxes and rear folders supported adjacent the path of travel of the folding boxes opposite the ejecting means aforesaid.

13. In a wrapping machine, an endless carrier provided with folding boxes, a pusher at one side of said carrier for forcing articles against wrappers and inserting the same into the folding boxes, a pusher at the opposite side of the carrier for ejecting the packages from said boxes, means for simultaneously operating both of said pushers, and means operating in conjunction with said pushers for turning in the corners of the wrappers as they are inserted into and ejected from said folding boxes.

14. In a wrapping machine, an endless traveling carrier provided with open ended folding boxes, a reciprocating feeding slide at one side of said carrier and operating substantially at a right angle thereto, a gear mounted in said machine and provided with a crank arm, a link connection between said arm and said slide, an ejecting slide removed from said feeding slide and operating at the opposite side of the carrier from the first slide at a right angle to said carrier, a second gear meshing with said first gear and provided with a crank arm, a link connection between said arm and said ejecting slide to simultaneously effect the movement of said feeding and ejecting slides, folders adjacent the edge of the carrier and interposed in the course of travel of the carrier between the feeding and ejecting slides and folders standing at the opposite side of the carrier from said ejecting slide and arranged to operate on the packages ejected thereby.

15. In a wrapping machine, a traveling carrier provided with open ended folding boxes, a reciprocating feeding slide at one side of said carrier and operating substantially at a right angle thereto, an ejecting slide removed from said feeding slide and operating at the opposite side of the carrier from the first slide at a right angle to said carrier, complementary gears mounted in said machine and having operative connection with said feeding and ejecting slides, whereby packages are simultaneously fed and ejected from said boxes, folders adjacent to and parallel with the edge of the carrier and interposed in the course of travel of the carrier between the feeding and ejecting slides, folders standing at the opposite side of the carrier from said ejecting slide and arranged to operate on the packages ejected thereby, corner folders in the folding boxes and corner folders opposite the ejecting slide and located within said folder standing at the opposite side of the carrier from said ejecting slide.

16. In a wrapping machine, a traveling

carrier having folding boxes provided with corner folders, means for simultaneously inserting and ejecting wrappers into and out of said folding boxes and edge folding means disposed at the side of the carrier and in the path of travel of the wrappers carried thereby.

17. In a wrapping machine, a traveling carrier having folding boxes provided with corner folders, means for simultaneously inserting and ejecting wrappers and articles to be wrapped into and out of said folding boxes and edge folding means disposed at the side of the carrier and in the path of travel of the wrappers carried thereby, corner folders at the side of the carrier in the path of the ejecting movement of the wrappers and side folding means enclosing said last mentioned corner folders and in the path of movement of the ejected wrappers, whereby said sides of the wrapper may be movable between the inner surface of said side folding means and opposite surface of said rear corner folders to move the projecting portions of said wrapper down over the edge of said article.

18. In a machine of the character described, a wrapper magazine, means for intermittently feeding out single wrappers from said magazine, a guide passage for the wrappers, and adjustable stop for positioning the wrappers at the end of said guide passage, means for advancing the wrappers fed out of the magazine along said guide passage to said stop, a conveyor having folding boxes, means for advancing said conveyor and for registering the folding boxes with the positioned wrappers, a pusher at the side of the conveyor for forcing the positioned wrappers about an article to be enclosed and in folded form into the folding boxes, folders in said boxes for operating on the wrappers as the same are inserted therein and means stationed at a subsequent point in the line of travel of the conveyor for simultaneously ejecting the advanced partially enclosed packages from said boxes during the operation of the pusher.

19. In a machine of the character described, a wrapper magazine, means for intermittently feeding out single wrappers from said magazine, a guide passage for the wrappers, a stop for positioning the wrappers at the end of said guide passage, means for advancing the wrappers fed out of the magazine along said guide passage to said stop, a conveyor having folding boxes, means for advancing said conveyor and for registering the folding boxes with the positioned wrappers, a pusher at the side of the conveyor for forcing the positioned wrappers about the articles to be enclosed and in folded form into the folding boxes, folders in said boxes for operating on the wrappers as the same are inserted therein and means operating simultaneously with the movement of said pusher and stationed at a subsequent point in the line of travel of the conveyor for ejecting the wrappers from said boxes.

20. In a machine of the character described, a wrapper magazine, means for intermittently feeding out single wrappers from said magazine, a guide passage for the wrappers, a stop for positioning the wrappers at the end of said guide passage, means for advancing the wrappers fed out of the magazine along said guide passage to said stop, a conveyor having folding boxes, means for advancing said conveyor and for registering the folding boxes with the positioned wrappers, a pusher at the side of the conveyor for forcing the positioned wrappers about the articles to be enclosed and in folded form into the folding boxes, folders in said boxes for operating on the wrappers as the same are inserted therein, means operated by the movement of said feeding means and stationed at a subsequent point in the line of travel of the conveyor for ejecting the wrappers from said boxes and folding devices arranged in the path of the wrappers ejected from the folding boxes.

In testimony whereof I have affixed my signature.

FRANK W. LEV.
